UNITED STATES PATENT OFFICE.

HENRY BARKSCHAT, OF LOS ANGELES, CALIFORNIA.

MACHINE FOR MOLDING CONCRETE POSTS AND THE LIKE.

Application filed February 24, 1925. Serial No. 11,053.

To all whom it may concern:

Be it known that I, HENRY BARKSCHAT, a citizen of the United States, residing at Los Angeles, in the county of Los Angeles and 5 State of California, have invented new and useful Improvements in Machines for Molding Concrete Posts and the like, of which the following is a detailed description.

This invention relates to machines for 10 molding plastic material by the well known centrifugal method, and has as its principal object to provide a machine of this type having certain characteristics which render it capable of greatly expediting casting operations.

I produce the desired result by jarring or 15 vibrating the mold during its rotation, this effect being given by so constructing the machine or mold clamping mechanism that 20 the mold ends gyrate with respect to each other, or more broadly, so two longitudinally spaced points on the mold gyrate with respect to one another. This movement of 25 the mold tends to hasten the disengagement of the excess water in the plastic mass and to compact the aggregate deposited on the 30 mold walls much more quickly and solidly than when the mold is rotated without such vibration or gyration. For instance, in 35 casting concrete light posts weighing 1500 pounds, I find that it requires approximately twelve or fifteen minutes of usual centrifuge operation to complete the casting operation, while it takes only approximately five minutes to complete the operation when 40 the mold is gyrated in the manner described. The economic advantage thus gained is obvious and need not be further discussed.

The following detailed description will 45 set forth several ways of accomplishing the desired end. Reference will be had to the accompanying drawings, in which:

Fig. 1 is a side elevation of a machine embodying my invention;

Fig. 2 is an end elevation of Fig. 1;

Figs. 3 and 4 are diagrammatic views illustrating certain characteristics of variational forms of the machine;

Fig. 5 is an end elevation of a variational 50 form of mold used in connection with the machine; and

Fig. 6 illustrates another variational form of the machine.

In order to fully disclose my invention I have illustrated a well known type of centrifuge altered in a manner to gain the desired end; and will describe the operation of this machine and the construction of a typical mold with some particularity. However, it will be understood the drawings and 55 description are merely illustrative of the invention and are not to be considered as limitative thereon, for the invention is equally well applicable to other machines and molds.

Cylindrical mold 10 is provided with annular collars 11 and 11^a at two longitudinally spaced points therealong, and in the embodiment of the invention first to be described it will be assumed that these collars and the mold bore are substantially coaxial. Centrifuge 12 is made up of two substantially identical units 13, 14, adapted to take collars 11 and 11^a, respectively. However, it will be later pointed out that the invention, in its broader aspects, is not limited to 60 a machine having two point engagement 65 with the mold.

Units 13 and 14 have cylindrical mold carriers or open ended drums 15 and 16, 70 carrying chuck jaws 17 and 18, respectively, which are arranged in any suitable manner (not shown, since many suitable jaw actuating means are well known to those skilled in the art) to engage collars 11^a and 11 75 firmly and thus hold the drums and molds against relative longitudinal and rotary movement. The jaws are movable to allow 80 easy insertion and withdrawal of the mold.

Each drum is supported by rollers 19 85 which are journaled on frames 20 and engage drum rollways 21 in the usual manner, units 13 and 14 being set up so the drum axes 90 are approximately alined.

In order that frame 10 need not be built 95 excessively heavy to withstand the vibrations set up by the drums during rotation thereof, it is preferable that roller shafts 19^a be yieldingly mounted in the frame. For instance, they may be mounted in the manner set forth in United States Letters Patent No. 1,391,164, issued to me September 100

20, 1921; shaft boxes 22 being slidably mounted in the frame and being urged towards the drum axes by adjustable springs 23.

5 Belts 24 are run over crowned portions 25 of the drums and are driven from power shaft 26 by pulleys 27. While the drawings indicate that both drums are positively driven, it is usually desirable to apply power 10 to only one, the other merely being guided in its movement by the associated set of rollers 18.

Now it is the practice to hold the mold concentrically in both drums, and rotation 15 of the aligned drums causes simple rotation of the mold. However, I so alter the machine that either or both ends of the mold are eccentrically mounted in the drums, and by this alteration set up gyration of one end 20 of the mold with respect to the other. The eccentric mounting of the mold may be accomplished in a variety of manners, all lying within the scope of the invention, considered in its broader aspects, and I will 25 describe several of such mountings.

First take the case where only one end of the mold is eccentrically mounted. Referring to Fig. 3, chuck jaws 18 in drum 16 are adapted to hold collar 11 concentrically within said drum, while jaws 17 are offset with respect to the axis of rotation of drum 15 and therefore hold the left hand end of the mold (as viewed in Fig. 1) eccentrically within said drum. Drum rotation 30 consequently gyrates the ends of the molds with respect to one another (the chuck jaws being arranged to grasp the mold collars in a manner to allow this relative movement of the mold ends) and this movement of the 35 mold greatly expedites the disengagement of the excess water originally present in the plastic mass within the mold, and hastens the compacting of the aggregate thrown to the inner face of the mold by centrifugal 40 force.

In the instance just cited, the left hand end of the mold will gyrate through a path of greater diameter than does the right hand end. If it be desired that the mold 50 ends gyrate equally (assuming that collars 11 and 11^a are equally spaced from the mold ends) jaws 17 and 18 will be equally offset with respect to their associated drums (see Fig. 4) but to fulfill the described gyroscopic conditions, the jaws must be equally and diametrically oppositely offset with respect 55 to the common drum axis.

Of course, the relative jaw offset need not 60 be 180° in order to cause relative end gyration when it is unessential that the gyroscopic paths of the two eccentrically mounted ends be of equal diameter, but it is necessary that the jaws be so relatively arranged that they are out of axial alinement; otherwise, the mold, as a whole, would gyrate 65

but there would be no relative gyration between its ends. With the machine initially set to bring about the desired relationship of jaw eccentricities, it is unnecessary to adjust the machine in order to maintain this 70 relationship upon the exchange of molds if the two drums be properly interconnected through the driving or other suitable mechanism. If the drums are capable of independent rotation when the mold is removed, 75 it is necessary to make sure the chuck jaws are disaligned before clamping the mold in position.

The described gyroscopic effect may also be obtained with coaxial drums and chuck 80 jaws, by interposing eccentric bushings between either or both jaws and the mold, or by providing mold 10 with eccentric collars 11^b (Fig. 5) in place of coaxial collars 11, 11^a. 85

Where the size of the mold permits, a single centrifuge unit may be employed (see Fig. 6) the mold 10^a being held intermediate its ends by jaws 18^a so its axis extends angularly with respect to the axis of drum 16^a. It is apparent that drum rotation will cause gyration of the mold ends with respect to one another. 90

While I have illustrated and described certain manners in which the machine may be fashioned to accomplish a particular nature of mold gyration, it will be understood such other means as may be employed to accomplish this lie within the scope of my invention, and therefore I do not wish 95 to be limited to the machine as illustrated and described except for such limitations as a fair interpretation of the appended claims may import.

Having described a preferred form of my 105 invention, I claim:

1. In a machine of the character described, a frame, a mold, and means rotatably supporting the mold in the frame and adapted to gyrate one end of the mold with 110 respect to the other end.

2. In a machine of the character described, an elongated mold and means at two longitudinally spaced points along the mold adapted to rotatably support said 115 mold in a manner to gyrate said points with respect to one another.

3. In a machine of the character described, a frame, a drum rotatably supported in the frame, a mold, and means adapted to hold the mold and drum against relative 120 rotation and to hold the mold in eccentric relation to the drum.

4. In a machine of the character described, a frame, a drum rotatably supported in the frame, a mold, and a chuck in the drum adapted to hold the mold in eccentric relation to the drum. 125

5. In a machine of the character described, a frame, a mold, a plurality of roll- 130

ers yieldably mounted in the frame and adapted to support the mold rotatably in the frame, and means for gyrating one end of the mold with respect to the other end.

5 6. In a machine of the character described, two rotatable drums arranged substantially in axial alinement, an elongated mold extending through the drums, and means adapted to connect the drums and

mold in a manner whereby coincident rotation of the drums imparts gyratory movement to one end of the mold with respect to the other end. 10

In witness that I claim the foregoing I have hereunto subscribed my name this 19¹⁵ day of January, 1925.

HENRY BARKSCHAT.
